PISTON

Lewis P. Kalb, Grosse Pointe Village, and Andre J. Meyer, Detroit, Mich., assignors to Continental Motors Corporation, Detroit, Mich., a corporation of Virginia

Application January 16, 1933, Serial No. 651,996

5 Claims. (Cl. 309—14)

This invention relates to pistons for use in internal combustion engines and has among its objects the provision of an improved piston construction and method of making same.

5 A further object of our invention resides in the provision of a piston of relatively light weight and having good heat conductive and wearing qualities. This invention combines in a novel way the desirable qualities of the present day 10 aluminum pistons with the desirable wearing qualities of the cast iron piston.

In general, our invention consists in the provision of a piston having an aluminum head and a cast iron skirt or cross-head portion, these parts 15 being connected in an improved manner whereby in operation under the influence of heat, the piston will maintain its desired shape and other characteristics without warping and scuffing.

A further feature of our invention resides in 20 the provision of a novel method of manufacturing a piston whereby the cooperating piston parts are interconnected preferably by casting one into interengaged relation with the other. In our preferred form the aluminum head is cast in interengaging relationship with the cast iron skirt portion.

In carrying out our invention in the specific 25 form illustrated, we have provided all contacts between the aluminum and cast iron in the form 30 of frusto-conical surfaces whose apices lie at the intersection of the piston axis and the piston pin or boss axis. Thus, we have provided a contact 35 between the head and skirt in the form of a frusto-conical surface whose apex lies at the intersection of the piston and boss axes, the axis 40 of the cone lying along the piston axis.

The piston head is formed with bosses each 45 having an inner cylindrical bore for receiving the usual piston pin. In order to prevent binding, under heat expansion, at the bosses, we have formed a further frusto-conical surface contact between the skirt and each boss, the apex thereof lying at the aforesaid intersection of the piston and boss axes. The axes of these cones lie along 50 the boss or pin axes adjacent each other.

By reason of the foregoing arrangement, all 55 contacting surfaces between the piston parts are subjected to sliding on each other, the expansion and contraction taking place with respect to a common point whereby binding tendencies are eliminated and the piston will, at all times maintain its desired cylindrical shape without distortion heretofore experienced in composite

Referring to the accompanying drawing which illustrates one embodiment of our invention,

Fig. 1 is a side elevation view of our piston, partly in cross-section to illustrate one of the bosses,

Fig. 2 is a side elevation view at right angles to that illustrated in Fig. 1,

Fig. 3 is a section along the line 3—3 of Fig. 2, and

Fig. 4 is a sectional elevation view of the piston 10 skirt, illustrating in dotted lines the manner of casting the head thereto.

Reference character A represents the piston assembly comprising a head structure 10 and a skirt or cross-head structure 11, the former being of a relatively light weight material having good heat conductivity such as the usual aluminum alloy ordinarily used in pistons for example, and the skirt 11 being of a material having good 15 wearing qualities with the engine cylinder, such as cast iron for example. The head 10 preferably has a diameter slightly less than skirt 11, the latter having a working fit with the cylinder and the head carrying the usual piston rings (not shown) for holding the pressure and for carrying 20 off heat from head 10 to the cylinder walls.

Head 10 has depending therefrom, the arms 12 extending inwardly of the upper end of skirt 11. Each arm 12 is provided with a laterally extending boss 13, the bosses having piston pin-receiving bores 14, whose common axis 15 intersects the piston axis 16 at the point 17. We have not shown the piston pin in the bores 14 as this is well known in the art and forms no part of this 25 invention per se.

Skirt 11 has diametrically opposite openings receiving the respective bosses 13, these openings being in the form of a frusto-conical surface 18, whose axis is the axis 15 aforesaid. The cones including surfaces 18 are diagrammatically represented at x and x' in Fig. 1, these cones having 30 their apices at 17.

The upper end of skirt 11 is formed with a circumferentially extending frusto-conical surface 19, whose axis is the axis 16 aforesaid. The cone including surface 19 is diagrammatically represented at y in Fig. 1, this cone having its apex at 35 17.

We preferably form the head 10 by casting the aluminum (in a suitable mold) in the form shown 40 whereby the head bosses 13 form companion frusto-conical surfaces 18' in engagement with surfaces 18, and also the frusto-conical annular surface 19' in engagement with surface 19. The head and skirt are thus interengaged or inter- 45 50 55

locked by the frusto-conical surfaces and thereby held together. Furthermore, under heat variations, relative expansion and contraction between the head and skirt will take place by a sliding of surfaces 18, 18' and 19, 19' in the direction of the cones forming these surfaces, whereby binding or distorting tendencies are eliminated.

It will be noted that we have a piston which is free from radially abutting surfaces which would bind and cause distortion under heat; in our piston all abutting surfaces radially of the piston lie in cones as aforesaid whereby to permit free relative sliding without distortion.

We desire to point out that we do not limit our invention to the particular arrangement of parts illustrated as various changes may be made within the scope of our invention as defined by the appended claims. For example, the location of the frusto-conical surfaces axially of the piston is not important to a successful working of our invention, as long as these surfaces are parts of cones having apices at a common point, or approximately so, in keeping with the beneficial results desired. While the best results of our invention are obtained by locating this common point at the intersection of the piston and boss axes, a shifting of this point within reasonable limits may, of course, be resorted to in keeping with the teachings of our invention.

30. What we claim as our invention is:

1. In a piston, a skirt structure formed with diametrically opposite openings bounded by frusto-conical surfaces respectively lying in a cone whose apex is located substantially at the intersection of the piston axis and the axis of said openings, said skirt having an outer circumferential frusto-conical surface lying in a cone whose axis substantially coincides with the piston axis and whose apex is located substantially at the intersection aforesaid, and a head structure provided with bosses respectively extending into said skirt openings, said head structure having frusto-conical surfaces complementary to said skirt surfaces and in sliding contact therewith.

45. 2. In a piston, a skirt structure formed with

diametrically opposite openings bounded by frusto-conical surfaces respectively lying in a cone whose apex is located substantially at the intersection of the piston axis and the axis of said openings, said skirt having an outer circumferential frusto-conical surface lying in a cone whose axis substantially coincides with the piston axis and whose apex is located substantially at the intersection aforesaid, and a head structure provided with bosses respectively extending into the said skirt openings, said bosses having frusto-conical surfaces fitting within the surfaces of said skirt openings respectively, said head structure having a frusto-conical surface engaging said circumferential frusto-conical surface of the skirt.

3. In a piston, a head structure, a skirt structure, one of said structures having a boss adapted to receive a piston pin, said boss having a frusto-conical surface lying in a cone whose apex lies within the piston, and whose axis lies substantially along the axis of the boss, the other of said structures having a surface complementary to said frusto-conical surface and in sliding contact therewith whereby relative transverse movements due to expansion may freely take place between said structures without binding and distortion thereof.

4. In a piston, a head structure, a skirt structure, one of said structures having a boss adapted to receive a piston pin, said boss having a frusto-conical surface lying in a cone whose axis lies substantially along the axis of the boss, the other of said structures having a surface complementary to said frusto-conical surface and in sliding contact therewith, the apex of said cone lying substantially in the axis of the piston.

5. In a piston, an aluminum head structure formed with a lateral boss, and a cast iron skirt having an opening receiving the boss, said opening and boss having engaging frusto-conical relative sliding surfaces lying in cones having axes extending transverse to the piston axis and their apices lying within the piston.
